(57) **CLAIM**

The ornamental design for a portable communications device, as shown and described.

DESCRIPTION

FIG. 1 is a front perspective view of the portable communications device showing my design;

FIG. 2 is front view thereof;

FIG. 3 is a side view thereof;

FIG. 4 is an opposing side view thereof;

FIG. 5 is a rear view thereof;

FIG. 6 is a top view thereof;

FIG. 7 is a bottom view thereof;

FIG. 8 is a front perspective view of an alternative embodiment of the portable communications device illustrating my design with exterior surface regions having contrasting materials. As shown by the speckle-shaded portions of the device, portions of the exterior surface are formed of a first material type. The other regions of the device are formed of other materials having different visual and/or tactile characteristics relative to the first material.

FIG. 9 is front view thereof;

FIG. 10 is a side view thereof;

FIG. 11 is an opposing side view thereof;

FIG. 12 is a rear view thereof;

FIG. 13 is a top view thereof; and,

FIG. 14 is a bottom view thereof.
